UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed November 15, 1919. Serial No. 338,290.

To all whom it may concern:

Be it known that I, WILLIAM L. MCGRATH, a citizen of the United States, residing at Elmira, in the county of Chemung and State 5 of New York, have invented certain new and useful Improvements in Engine Starters, of which the following is a specification.

My invention relates to an engine starter used more particularly for the purpose of 10 starting an internal combustion engine and has for its general object the provision of a novel and efficient construction of the drive or transmission portion thereof. My drive is of the type known as the Eclipse-Bendix 15 characterized by a driving shaft driven directly or indirectly by the prime mover, such as an electric motor, a driven shaft, such as a screw shaft operatively connected with the driving shaft by a yielding driving 20 connection, such as a drive spring, and a driving member such as a pinion, mounted on the screw shaft for longitudinal movement thereon for advancement to engagement with an engine member, such as the 25 fly wheel, and for rotary movement therewith after such engagement. The more specific object of my invention is to provide between the two shafts a friction clutch in addition to the drive spring adapted more particularly to protect the spring against the 30 effect of an excessive torque, beyond the safety limit of such spring, and also to protect the other parts of the starter from injury.

In the drawings, Fig. 1 is a sectional elevation of an engine starter embodying my invention; Figs. 2, 3, 4 and 5 sections on the corresponding section lines of Fig. 1; Fig. 6 an elevation of the engaging ends of 40 the two driving sleeves; and Figs. 7, 8, 9 and 10 detail views of these two sleeves.

The drive illustrated is one of a number in which my invention may be embodied. Also, while I have shown the single reduction type and the outboard type of drive, it will be understood that my invention is 45 applicable to the double reduction type and the inboard type of drive.

Describing the construction shown, the 50 electric motor 1 has an extended armature shaft 2, forming a driving shaft, on which are mounted the several parts comprising the drive. Upon the inner portion of the shaft 2 there is mounted and secured thereto a

driving element in the form of a sleeve and 55 preferably comprising two parts or sleeves 3 and 4, although a single part would satisfy my invention in its broader aspect. The sleeve 3 is secured to the shaft 2 in suitable manner as by the transverse pin 5, so that 60 such sleeve has a fixed relationship to the shaft. This sleeve has a flanged head 6 provided with inclined or cam jaws 7 for a purpose hereinafter described. The other sleeve 4 is mounted loosely upon the shaft 2 and capable of axial or longitudinal movement thereof. It is likewise provided with a flanged head 8 having cam jaws 9 corresponding to jaws 7 and normally engaging the same.

A driven sleeve 10 is mounted upon the sleeve 3 for rotary movement therewith and a limited rotary movement thereof, and is provided with a cylindrical portion or shell 11 extending outwardly and over the sleeves 75 3 and 4. This shell is operatively connected with the sleeve 4 by a friction clutch which here comprises a series of plates or disks 12 interlocked with longitudinal grooves 13 in the outer surface of the sleeve 4 and a series 80 of plates or disks 14 interlocked with longitudinal slots 15 in such shell. A locking ring 16 holds the disks together. A coiled spring 17 is arranged within the shell and encircles the sleeve 4, with one end bearing 85 against the head 8 and the other against the friction clutch.

The driven shaft is a screw shaft 18 of the hollow type mounted on the shaft 2 and the driving member is a pinion 19 mounted 90 on the screw shaft for automatic longitudinal movement therewith and adapted to engage the engine member such as a fly wheel 20. The screw shaft has the usual driven head 21 at one end.

The driven sleeve 10 and the head 21 are operatively connected by a yielding driving connection which is here a coiled drive spring 22 anchored at its ends to such sleeve and head by the studs or bolts 23 and 24 respectively.

Describing a cycle of operation and beginning with the parts in their normal position shown, the rotation of the motor rotates the shaft 2 and consequently the connected parts including the sleeves, spring and screw shaft, with the result that the pinion will be automatically meshed with

and will drive the fly wheel. When the engine has started on its own power the pinion will be automatically demeshed in the usual manner.

5 Between the sleeves 3 and 4 and the screw shaft, the torque is transmitted through the friction clutch and the drive spring. After full mesh is obtained and the pinion is in position to drive the fly wheel, the resistance 10 causes the sleeve 4 to move longitudinally relative to the sleeve 3, owing to the cam action of the jaws 7 and 9, with the result that an increased pressure is applied to the friction clutch through the spring 17, 15 sufficient to enable the clutch to take the load and transmit the necessary torque required normally. The construction is such that this pressure is less than the safety load limit of the spring, and hence the 20 torque is transmitted through the drive spring without danger of breaking it or causing a setting thereof, and likewise other parts of the starter system are protected against injury. The pressure on the clutch through 25 the spring 17 increases up to a predetermined point as the torque increases which causes a greater or less relative longitudinal movement of the sleeve 4, but when a predetermined limit of torque, say 40 foot pounds, 30 is reached, as when the resistance of the fly wheel is excessive and liable to cause injury to or breakage of the drive, the clutch will slip and will not transmit the torque.

I claim:

35 1. An engine starter drive including a driving shaft, a driven shaft, said shafts being capable of angular displacement one with respect to the other, a driving member mounted on and driven by said driven shaft, 40 and driving means between the two shafts comprising a yielding driving connection and a friction clutch controlled by such displacement of the shafts.

2. An engine starter drive including a 45 driving shaft, a driven shaft said shafts being capable of angular displacement one with respect to the other, a driving member mounted on and driven by said driven shaft, and driving means between the two shafts 50 comprising a yielding driving connection and a friction clutch, said friction clutch controlled by the resistance transmitted to it through said yielding driving connection.

3. An engine starter including in 55 combination with a starting motor and a member of the engine to be started, a drive comprising a driving member adapted to engage the engine member and driven by the motor, and a yielding driving connection 60 and a friction clutch interposed in the line of transmission of power between the motor and engine member and adapted to be tightened to a pre-determined point as the starting operation proceeds and to there- 65 after slip in case of abnormal resistance.

4. An engine starter including in combination with a starting motor and a member of the engine to be started, a drive comprising a driving member adapted to engage the engine member and driven by the 70 motor, and a yielding driving connection and a friction clutch interposed in the line of transmission of power between the motor and engine member, said clutch having a resistance predetermined to substantially 75 equal the safety limit of the yielding driving connection.

5. An engine starter including in combination with a starting motor and a member of the engine to be started, a drive 80 comprising a driving member adapted to engage the engine member and driven by the motor, and a drive spring and a friction clutch interposed in the line of transmission of power between the motor and engine 85 member and controlled by the resistance transmitted to it through said drive spring.

6. An engine starter including, in combination with a starting motor and a member of the engine to be started, a drive 90 comprising a driving member adapted to engage the engine member and driven by the motor, and a coiled torsion drive spring and a friction clutch interposed in the line of transmission of power between the motor and the engine member, the spring being arranged concentric of the clutch.

7. An engine starter drive including a driving shaft, a driving and a driven head, the former being driven by such shaft, a 100 friction clutch between the heads, a driven shaft, a driving member mounted thereon for engagement with a member of the engine to be started, and a yielding driving connection between the driven head and the driven shaft, said driven head and driven shaft being capable of an angular displacement one with respect to the other and the clutch being controlled by such displacement.

8. An engine starter drive including a driving shaft, a driving and a driven head, the former being driven by such shaft, a friction clutch between the heads, a driven shaft, a driving member mounted thereon for engagement with a member of the engine to be started, and a drive spring forming the drive connection between the driven head and the driven shaft, said driven head and driven shaft 115 being capable of an angular displacement one with respect to the other and the clutch being controlled by such displacement.

9. An engine starter drive including a driving shaft, a driving and a driven head, the former being driven by such shaft, a friction clutch between the heads, a driven shaft, a driving member mounted thereon for engagement with a member of the engine 120 to be started, and a coiled drive spring hav- 130

ing its ends anchored to the driven head and the driven shaft respectively, said driven head and driven shaft being capable of an angular displacement one with respect to the other and the clutch being controlled by such displacement.

10. An engine starter drive including a driving shaft, a driving and a driven head, the former being driven by such shaft, a friction clutch between the heads, a driven shaft, a driving member mounted thereon for engagement with a member of the engine to be started, and a yielding driving connection between the driven head and the driven shaft, said driving head being formed in two parts normally held together with a yielding pressure but adapted to separate; one with respect to the other.

11. An engine starter drive including a driving shaft, a driving and a driven head, the former being driven by such shaft, a friction clutch between the heads, a driven shaft, a driving member mounted thereon for engagement with a member of the engine to be started, and a yielding driving connection between the driven head and the driven shaft, said driving head being formed of two sleeves in axial alinement and normally held in engagement at their adjacent ends with a yielding pressure.

12. An engine starter drive including a driving shaft, a driving and a driven head, the former being driven by such shaft, a friction clutch between the heads, a driven shaft, a driving member mounted thereon for engagement with a member of the engine to be started, and a yielding driving connection between the driven head and the driven shaft, said driving head being formed of two sleeves in axial alinement and having at their adjacent ends clutch members normally in engagement.

13. An engine starter drive including a driving shaft, a driving and a driven head, the former being driven by such shaft, a friction clutch between the heads, a driven shaft, a driving member mounted thereon for engagement with a member of the engine to be started, and a yielding driving connection between the driven head and the driven shaft, said driving head being formed of two sleeves in axial alinement, the first of which is secured to the driving shaft and the other of which is mounted to rotate therewith and partially thereof and to move longitudinally thereof towards and away from the first sleeve, said friction clutch cooperating with said second sleeve.

14. An engine starter drive including a driving shaft, a driving and a driven head, the former being driven by such shaft, a friction clutch between the heads, a driven shaft, a driving member mounted thereon for engagement with a member of the engine to be started, and a yielding driving con-

nexion between the driven head and the driven shaft, said driving head being formed of two sleeves in axial alinement, the first of which is secured to the driving shaft and the other of which is mounted to rotate therewith and partially thereof and to move longitudinally thereof towards and away from the first sleeve, the adjacent ends of the two sleeves having corresponding jaws yieldingly held together but tending to open and separate when the driving head is operated, and said friction clutch cooperating with said second sleeve.

15. An engine starter drive including a driving shaft, a driving and a driven head, the former being driven by such shaft, a friction clutch between the heads, a driven shaft, a driving member mounted thereon for engagement with a member of the engine to be started, and a yielding driving connection between the driven head and the driven shaft, said driving head being formed of two sleeves in axial alinement, the first of which is secured to the driving shaft and the other of which is mounted to rotate therewith and partially thereof and to move longitudinally thereof towards and away from the first sleeve, the adjacent ends of the two sleeves having corresponding jaws yieldingly held together but tending to open and separate when the driving head is operated, and said friction clutch cooperating with said second sleeve, and a spring between the clutch and the movable sleeve.

16. An engine starter drive including a driving shaft, a driving and a driven head, the former being driven by such shaft, a friction clutch between the heads, a driven shaft, a driving member mounted thereon for engagement with a member of the engine to be started, and a yielding driving connection between the driven head and the driven shaft, said driving head being formed of two sleeves in axial alinement, the first of which is secured to the driving shaft and the other of which is mounted to rotate therewith and partially thereof and to move longitudinally thereof towards and away from the first sleeve, the adjacent ends of the two sleeves having corresponding cam jaws.

17. An engine starter drive including a driving shaft, a driving and a driven head, the former being driven by such shaft, a friction clutch between the heads, a driven shaft, a driving member mounted thereon for engagement with a member of the engine to be started, and a yielding driving connection between the driven head and the driven shaft, consisting of a coiled driving spring anchored at its ends to the driven head and the driven shaft respectively and encircling the two heads.

18. An engine starter drive including a driving shaft, a driving and a driven head,

- the former being driven by such shaft, a friction clutch between the heads, a driven shaft, a driving member mounted thereon for engagement with a member of the engine 5 to be started, and a yielding driving connection between the driven head and the driven shaft, said clutch and driving head having a relative movement, one with respect to the other.
- 10 19. An engine starter drive including a driving shaft, a driving and a driven head, the former being driven by such shaft, a friction clutch between the heads, a driven shaft, a driving member mounted thereon for engagement with a member of the engine 15 to be started, and a yielding driving connection between the driven head and the driven shaft, said clutch being interlocked with the two heads, said driving connection 20 being a coiled spring encompassing the clutch and the two heads.
20. An engine starter drive including a driving shaft, a driving and a driven head, the former being driven by such shaft, a friction clutch between the heads, a driven shaft, a driving member mounted thereon for engagement with a member of the engine 25 to be started, and a yielding driving connection between the driven head and the driven shaft, said driven head and driven shaft being capable of angular displacement one with respect to the other, 30 said clutch comprising friction plates, one set of which cooperate with one head and 35 the other set with the other head, said clutch having tightening means controlled by said angular displacement.
21. An engine starter drive including a driving shaft, a driving and a driven head, the former being driven by such shaft, a friction clutch between the heads, a driven shaft, a driving member mounted thereon for engagement with a member of the engine to be started, and a yielding driving connection between the driven head and the driven shaft, said clutch comprising friction plates, one set of which cooperate with one head and the other set with the other head, and a spring between the plates and the driving head. 40 50
22. An engine starter drive comprising a driving shaft, a driving head secured thereto and formed as two sleeves in axial alignment, one being movable relatively to the other longitudinally of the shaft and such sleeves being normally engaged at their adjacent ends, a driven head mounted on the driving head and formed as a sleeve projecting over such driving head, a friction clutch between such latter sleeve and the movable sleeve, a spring between the clutch and the movable sleeve, a screw shaft mounted on the driving shaft, a driving member mounted on the screw shaft for rotary movement therewith and longitudinal 55 movement thereon, and a spring driving connection between the screw shaft and the driven head. 60 65

WILLIAM L. McGRATH.
